UNITED STATES PATENT OFFICE.

WILLIAM H. SWARTZ, OF YORK, PENNSYLVANIA.

DOGLESS-DIAL ATTACHMENT FOR KNITTING-MACHINES.

1,364,218.

Specification of Letters Patent.

Patented Jan. 4, 1921.

Application filed June 28, 1919. Serial No. 307,403.

To all whom it may concern:

Be it known that I, WILLIAM H. SWARTZ, a citizen of the United States, residing at York, in the county of York and State of Pennsylvania, have invented certain new and useful Improvements in Dogless-Dial Attachments for Knitting-Machines, of which the following is a specification, reference being had therein to the accompanying drawings.

This invention relates to a dogless dial attachment for knitting machines, and the object of the invention is to hold the dial stem stationary while other elements of the machine revolve around said stem, and at the same time allow the yarn to be carried in a revolving direction without any interference by any part that may be necessary to hold the stem stationary.

With this and other objects in view, my invention comprises certain novel constructions, combinations, and arrangements of parts as will be hereinafter specifically described, illustrated in the accompanying drawings, and more particularly pointed out in the appended claims.

In the drawings,

Figure 1 is a plan view of my apparatus showing the cover plate removed, while

Fig. 2 is a section taken on line 2—2, Fig. 1, looking in the direction of the arrows, the cover plate being on the casing.

Fig. 3 is a section taken on line 3—3, Fig. 2, looking in the direction of the arrows.

Fig. 4 is a perspective view of one of the cams.

Fig. 5 is a sectional view taken on line 5—5, Fig. 2.

Fig. 6 is a section taken on line 6—6, Fig. 2.

Fig. 7 is a fragmentary, perspective view of a portion of the casing showing the cam-supporting lug.

Fig. 8 is a sectional view taken on line 8—8, Fig. 1.

My invention, herein specifically described, is known to those skilled in the art of knitting by machinery as a "dogless dial" holder, and while all of the other parts of a knitting machine, such as more comprehensively disclosed in United States patent to G. L. Ballard, No. 1,012,966, issued December 26, 1911, I have not shown in the accompanying drawings, since I make no claims for the general elements of a knitting machine, all reference by name to such

missing parts will be readily understood by the trade in general.

Referring to the drawings by numerals, the purpose of my invention as clearly indicated in the foregoing statement of the object of the invention, is to hold the dial stem 1 stationary, while the other elements hereinafter described revolve around said stem 1, and at the same time allow the yarn, 65 passing down through the tubes hereinafter specifically described, to be carried in a revolving direction without any interference by any part that may be necessary to hold stem 1 stationary.

The stationary, ring-like casing 2 is attached through the medium of fastening means 3 to preferably two braces 4, which braces extend downwardly, as usual with such braces in knitting machines (see Ballard patent above referred to), and are secured to some stationary part of the machine; these braces 4 constitute a support for the casing 2, Fig. 1.

The flat ring 5 is fastened by means of 80 screws 6 to the lower edge of casing 2, and a flat ring 7 is fastened by screws 8 to the hub 9. The bottom disk 10 is mounted upon rings 5 and 7, being positioned within the casing 2 and bearing against an inwardly- 85 extending, horizontal, integral, annular rib 11 (Fig. 2).

The post 12 is attached to a rotatable part of a knitting machine, and cap 13 also revolves upon stem 1. A collar 14 is mounted upon post 12 and is retained in a set position thereon by means of set screws 15. The collar 14 is provided with an enlarged extension or lug 16 which is internally threaded as indicated by dotted lines 17 95 (Fig. 1) and threaded into this lug 16 is rod 18, which rod 18 is provided with a lock nut 19 for securing the rod in an adjusted position upon the lug and collar. The inner end of the rod 18 is extended through 100 the screw 20, and a cotter pin 21 is extended through the inner end of the rod holding the rod upon the screw 20. A yoke arm 22 has its inner yoke end 23 straddling (Fig. 3) stem 1 and its outer end is held by screw 105 24 upon the top of post 12. The yoke arm 22 is bent upwardly intermediate its ends, and in the highest portion 22^a is formed an elongated slot 25, in which slot 25 works the lower end of screw 26, this screw 26 110 being threaded through the bottom disk 10 whereby, when post 12 and cap 13 are ro-

tated, bottom disk 10 will be also rotated simultaneously.

Extending from the inner face of the bottom disk 10 are integral, internally-threaded lugs 27, and into each lug 27 is threaded (Fig. 8) the lower end of the yarn-receiving tubes 28, which tubes are provided with flared, upper ends for facilitating the threading of the yarn down through the tubes to the needles of the knitting machine. Upon each tube 28 is mounted a roller 29. Any number of tubes may be used or employed, but I have preferably shown in the present embodiment of my invention 15 four tubes arranged in pairs.

The hub 9 is provided with integral, horizontal projections 30, each being provided with a threaded socket 31, into which socket is threaded a tapering pin 32; these pins 32 20 are in alinement with the rollers 29 on tubes 28; the rollers 29, however, pass these pins without striking the same. A set screw 33 fastens the hub 9 upon the stem 1, and auxiliary screws 34 center or retain the hub in 25 an adjusted position to a nicety upon the stem, at the will of the operator.

Formed at regular intervals around the face of casing 2 are integral, cam-supporting lugs 35, each lug being provided with 30 an aperture 36, whereby suitable fastening means, as indicated at 37, may be inserted through pivoted cams 38 and lugs 35, pivotally mounting the cams 38 upon the top of the lugs. Each cam 38 is elongated and 35 upon its inner edge or face and near its outer end is formed a pin-receiving socket 39 that is provided to receive the outer end of pin 32 (see Fig. 2). On the top of each lug 35 is a pin 40, and around said pin extends 40 an angular spring 41; one end of the spring 41 bears against the cam 38 near its outer end, and the other end of the spring bears against the casing 2, whereby the cam (all of the cams being similarly equipped 45 and operating in the same manner) is normally held in engagement with a pin 32, causing the outer end of the pin to be seated in socket 39 (Fig. 2), locking the hub 9 against rotation, as the hub, through the 50 medium of the pins and cams, will be held in a fixed, stationary position with respect to the stationary casing 2. However, as the bottom disk revolves, being driven by post 12, the tubes 28 will move around the hub, 55 causing the rollers 29 to engage the inner curved faces of cams 38, successively forcing the cams outwardly, against the action of the springs, permitting the tubes to pass the outer ends of the pins, and as soon as 60 the tubes have passed the particular cam, the spring will force the outer end of the cam inwardly, causing the cam to be seated again upon the pin, and while, in the present embodiment of my invention, I have shown 65 two cams being held from engagement with

their respective pins, there are several cams locked upon the pins at all times, consequently holding the hub 9 and stem 1 rigidly against rotary movement by reason of said hub and stem being locked upon the casing 2. 70

A cap or cover disk 42 is provided for covering the interior parts of the casing and keeping out dust or foreign objects. It is to be noted that hub 9 is provided with a tapering bore, whereby the upper end 9a of 75 the bore is wider than the lower end, allowing the adjusting action of screws 34 so that the adjustment may be secured to a nicety.

It will be understood that any number of 80 pins and cams may be employed in the manufacture of apparatus constructed in accordance with the present invention, and since minor alterations or changes may appear to one skilled in the art to which this 85 invention relates, in the construction of this apparatus, I wish it to be understood that I reserve the right to make alterations or changes or modifications as shall fairly fall within the scope of the appended claims. 90

What I claim is:

1. In a knitting machine of the class described, the combination with a support of a stationary casing attached to said support, a dial stem within said casing, a hub within 95 said casing, yarn-directing means carried by the casing and the hub, means for rotating said yarn-directing means, and means carried by the casing and the hub and permitting the yarn-directing means to pass 100 therebetween, but holding the casing, hub, and stem against rotary movement.

2. In a knitting machine, the combination with a rotatable post, a support, of a stationary casing carried by said support, a stem within said casing, yarn-directing means carried by said casing and said stem, a yoke arm provided with an upwardly-extending, central portion and being connected at its outer end to said rotatable post, said arm provided with an inner yoke end straddling said stem, said upwardly-extending, central portion of the arm being provided with an elongated aperture, means extending from said yarn-directing means into said elongated aperture whereby, when the post is rotated, the yarn-directing means will also be rotated, and means locking said casing and stem together. 110

3. In a knitting machine, the combination with a rotatable post, a support, of a casing carried by said support, a stem within said casing, yarn-directing means carried by said stem and casing and being provided with a screw extending downwardly therefrom, a 125 yoke arm provided with an elongated aperture intermediate its ends, fastened at its outer end to the post and slidably engaging at its inner end the stem, said screw having its lower depending end extending through 130

the elongated aperture of the arm, and means locking the casing and the stem together.

4. In a knitting machine, the combination with a support, of a stationary casing retained by said support, a stem within said casing, a hub upon said stem, pins extending from said hub, pivoted cams carried by said casing and adapted to engage said pins for locking the casing, hub, and stem together, and yarn-directing means carried by said casing and hub, and being adapted to pass between the pins and cams.

5. In a knitting machine, the combination with a support, of a stationary casing carried by said support, a dial stem within said casing, pins supported upon said stem, movable cam means supported upon said casing and being adapted to engage said pins for locking the casing and stem together, and yarn-directing means supported upon the casing and stem and being adapted to pass between the pins and cam means during its travel.

25 6. In a knitting machine, the combination with a support, of a casing carried by said support, said casing provided with an annular rib, a ring secured to the lower end of said casing, a dial stem within said casing, a hub on said stem, a ring secured to the hub, a bottom disk positioned between the rib of the casing and the ring secured to its lower end and resting upon the ring attached to the hub, tubes carried by said bottom disk, means for rotating said bottom disk, and means for locking said casing and the hub and stem together.

7. In a knitting machine, the combination with a support, of a casing carried by said support, a stem within said casing, a hub on said stem, a bottom disk provided with internally-threaded lugs upon its inner face, yarn tubes threaded into said lugs and extending through and beyond the upper and lower faces of said bottom disk, rollers on said tubes above said lugs, means for rotating said bottom disk and said tubes, and means formed upon said casing and hub locking said casing, hub, and stem together, but engaging said rollers of the tubes and allowing the tubes to pass therebetween.

8. In a knitting machine, the combination with a support, of a stationary casing carried by said support, a dial stem within said casing, a hub mounted upon said stem, said hub provided with a plurality of horizontal, integral projections, each projection provided with a threaded socket, a pin threaded into said socket, said casing provided with cam-supporting lugs contiguous to said projections of the hub, cams pivotally mounted upon said cam-supporting lugs, each cam having a socket for receiving the outer end of a pin, means for forcing the cams into engagement with said pins, and yarn-direct-

ing means carried by the casing and hub and being adapted to engage the cams and press the same away from the pins and pass between said cams and pins.

9. In a knitting machine, the combination with a support, of a stationary casing carried by said support, a stem within said casing, a hub carried by said stem, said hub provided with threaded sockets, pins threaded into said sockets, pivotally-mounted cams carried by said stationary casing, said cams provided with means for engaging said pins, and yarn-directing means rotatably mounted upon the casing and hub and being adapted to pass between the cams and the pins.

10. In a knitting machine, the combination with a support, of a stationary casing carried by said support, a dial stem within said casing and extending above and below the casing, a hub upon the stem and extending above and below the casing, yarn-directing means movably mounted upon the casing and the hub, and means permitting the yarn-directing means to pass therebetween and locking said hub, stem, and casing together.

11. In a knitting machine, the combination with a support, of a stationary casing carried by said support, a dial stem within said casing, a hub upon said stem, a pin carried by said hub, a curved cam pivotally mounted upon said casing and adapted to engage and be locked upon said pin, a disk rotatably mounted upon said casing and hub, yarn-directing tubes carried by said disk, rollers on said tubes, said rollers adapted to engage said cam and press the same away from said pin for permitting the passage of said rollers and tubes between the cam and pin, and means for rotating said disk.

12. In a knitting machine of the class described, the combination with a support, of a stationary casing carried by said support, said casing provided with a plurality of integral, cam-supporting lugs upon its inner face, a dial stem within said casing, a hub mounted upon said stem, said hub provided with a plurality of threaded, socketed projections within said casing, tapering pins threaded into said socketed projections, cams pivotally mounted upon said lugs of the casing and having curved inner faces and sockets near their outer ends, the pins normally resting at their outer ends in said sockets of the cams, springs interposed between said casing and cams and normally holding the cams in a locked position upon the pins, and yarn-directing means carried by the casing and hub and successively adapted to engage the cams, forcing the same against the action of the springs away from the pins and permitting the yarn-directing means to pass between the pins and the cams.

13. In a knitting machine, the combination with a support, of a stationary casing car-

ried by said support, a dial stem within said casing, a hub on said stem, pin and cam means supported upon the hub and upon the casing and coöperating for locking the casing, hub, and stem together, and yarn-directing means carried by the casing and hub and adapted to successively act upon the cam means for moving the same with respect to the pin means for permitting the yarn-
10 directing means to travel within the casing around the hub.

14. In a knitting machine, the combination of a support, of a stationary casing carried by said support, cam-supporting lugs formed upon said casing, cams pivotally mounted at one end upon said lugs, each cam provided with a socket near its outer end, pins upon said lugs, an angular spring extending around each pin and interposed between each cam and casing, a dial stem within said casing, a hub on said dial stem, horizontal projections extending from said hub, horizontal pins mounted upon said projections and adapted to engage at their outer ends the sockets on the cams, and yarn-

directing means rotatably mounted upon the casing and hub, and adapted to engage the inner faces of the cams for forcing the same to an unlocked position with respect to the pins, and permitting the yarn-directing 30 means to pass between the cams and the pins, substantially as shown and described.

15. In a knitting machine, the combination with a support, of a casing carried by said support, a hub provided with a tapering bore, a dial stem within said hub, means at one end of said hub for locking the same upon said dial stem, means at the opposite end of said hub for centering the hub upon the stem, locking means carried by the casing 35 and the hub for locking the stem, hub, and casing together, yarn-directing means rotatably mounted upon the casing and hub and being adapted to pass between the locking means, and means for rotating the yarn- 40 directing means.

In testimony whereof I hereunto affix my signature.

WILLIAM H. SWARTZ.
